HOSE SUPPORTER

Birdora H. White, Chicago, Ill., assignor to Parva Products Company, Hillsdale, Mich., a Corporation of Delaware

Application July 14, 1930. Serial No. 467,909

2 Claims. (Cl. 241—2)

This invention relates to supporters and has as a primary object to provide means for supporting articles of wearing apparel such as hose or the like which will exert no strain or pressure on either the shoulders or abdomen of the wearer.

The invention further contemplates the provision of a supporting belt which will exert no pressure on the shoulders or abdomen of the wearer together with means for combining this belt with a body encircling garment for supporting the belt in proper position.

Other objects and advantages of the invention will become more apparent as the following description proceeds, particularly when references is had to the accompanying drawings wherein,

Figure 1 is a front elevational view of a supporter formed in accordance with the teachings of this invention;

Figure 2 is a side elevational view of the supporter shown in Figure 1;

Figure 3 is a view similar to Figure 1 showing the invention combined with a corselette;

Figure 4 is a rear elevational view of the garment shown in Figure 3, and

Figure 5 is a side elevational view showing the supporter associated with a child's underwaist.

The invention contemplates in its broader aspects the combination with a body encircling garment such as a corset, corselette, girdle or child's undergarment, of a belt or the like suspended from the garment and provided with straps or the like for connection to an article of wearing apparel to be supported. Thus in use the articles of apparel will be supported by the belt while the belt in turn will be supported by the hips of the wearer. The garment is such that the belt is suspended from above the hips of the wearer at the back and extends around the body of the wearer from the waist line at the back to the middle and lower extremity of the trunk of the body in front where the two ends of the belt are brought together and secured in any desired manner, thus eliminating pressure on the abdomen of the wearer.

Referring then particularly to the drawings wherein like reference characters designate corresponding parts throughout all views, there is shown in Figure 1 a body encircling garment in the form of a girdle 10. This form of invention discloses a supporting belt 11 comprising a strip of flexible, non-elastic material wide enough to cover the curve of the hips and this belt is stitched or otherwise secured intermediate its ends to the girdle 10 adjacent the waist line

thereof in the back. The numeral 12 designates the line of stitching securing the belt 11 to the girdle 10, it being noted that the line of stitching extends across the back only whereby the front of the belt is loosely suspended.

The ends of the strip are cut on a bias as at 14 to parallel the waist line and are held at the front of the body by lapping one over the other and permanently or detachably securing the ends together. When thus connected the belt encircles the body of the wearer and by virtue of its connection to the girdle 10 in the back only, the remainder or front portion of the belt hangs freely to substantially the lower extremity of the trunk of the body.

Fixed to the belt at the front are straps 15 provided on their free ends with fasteners 16 for connection to a hose or the like. As indicated four of these straps are preferably provided so that two of the same may be engaged with each stocking adjacent the front thereof. It is also preferable to provide straps 17 suspended from the lower edge of the body encircling garment at the rear thereof, these straps being provided with fasteners 16 also for connection to the rear of the stocking so that three fasteners are provided for connection to each stocking.

It will be obvious that the straps 17 must have more play than the straps 15 because of the much greater strain on the same when the wearer is in a sitting position. For this reason the belt is pulled close to the body of the wearer in back by the stronger tension of the straps attached to the ends of the belt in front. If desired suitable tabs 19 and 20 may be fixed to the front and rear of the garment 10 for connection to a pad or the like whereby the same may be supported from the garment.

From the above it is believed that the structure of the invention will be clearly apparent. With the belt attached at the back only to a body encircling garment such as a corselette, waist or girdle 10, the front of the belt hangs substantially freely and does not engage the abdomen of the wearer. Thus the tension applied to the belt incident to the supporting of hose or the like from the same, tends only to draw the rear of the belt snugly against the back and hips or pelvic structure by which the strain is entirely supported and does not create any pressure whatsoever on the abdomen of the wearer. The belt is supported entirely by the hips, its attachment to the body encircling garment being for the sole purpose of maintaining the back

of the belt in position above the hips or at the waist line.

In Figures 3 and 4 a slightly modified form of construction is disclosed wherein the supporter comprises a belt associated with a body encircling garment such as the corselette 25. In this form of invention the belt 26 is stitched to the back of the corselette as at 27. As clearly illustrated, the ends of this belt are cut to parallel the waist line as indicated by the reference character 28 and are extended around the body of the wearer and connected together as at 29, below the abdomen. When so connected the belt encircles the body of the wearer and the rear portion of the belt is above the hips of the wearer, while the front portion of the belt is entirely below the hips. Hose supporting straps 30 are in this form secured to the ends of the belt at the front and additional straps 31 may, if desired, be secured to the lower end of the corselette 25 at the back.

In Figure 5 a still further modified form of invention is disclosed wherein the supporting belt 35 is stitched as at 36 to a child's underwaist or 25 the like 37. In this form of invention the hose supporting straps 38 are connected to the ends of the belt at the front thereof and no hose supporters are provided for engagement with the stockings at the back.

In each form of invention it will be noted that there is provided a belt associated with a body encircling garment in such a manner that the body encircling garment prevents the back of the belt from slipping below the hips of the wearer. Thus the belt is supported at the back and sides by the hips of the wearer, while the front of the belt is suspended below the hips and waist line of the wearer terminating at substantially the lower extremity of the trunk 40 of the body. The straps for supporting the articles of wearing apparel are connected to the belt at the front thereof and at the back they are connected to the body encircling garment when this garment is sufficiently long. Since 45 the belt does not extend directly around the body of the wearer but is rather arranged in an inclined plane or diagonally, pressure is only exerted across the back of the wearer and is

not exerted on the abdomen. It will be further apparent that the invention provides means for supporting articles of wearing apparel without exerting any pressure whatsoever on the shoulders or the abdomen of the wearer.

While several forms of the invention have been described with considerable detail, it is to be clearly understood that the description is for the purposes of illustration only and is not definitive of the limits of the inventive idea. The right is therefore reserved to make such changes in the details of construction and arrangement of parts as will fall within the purview of the attached claims.

What I claim as my invention is:

1. In a hose supporter, a strip of flexible inelastic material having an intermediate portion adapted to snugly engage the back of the wearer above the hips and having end portions adapted to extend forwardly and downwardly around the body of the wearer to the lower extremity of the trunk of the wearer, said strip of material being of sufficient length to be free from confining engagement with the front of the body of the wearer and the ends of said strip being secured together adjacent the upper edge only of said strip whereby the edges of the ends of said strip are free from connection to each other throughout the major portions of their lengths, and hose supporters secured to the free edges 105 of the ends of said strips.

2. In a hose supporter, a strip of flexible inelastic material having an intermediate portion adapted to snugly engage the back of the wearer above the hips and having end portions adapted 110 to extend downwardly and forwardly around the body of the wearer to adjacent the lower extremity of the trunk of the wearer, the ends of said strip being cut on a bias, and the said ends of the strip being secured together adjacent the upper edge only of the strip whereby the edges of the ends of said strip are free from connection to each other throughout the major portion of their length, means for maintaining 115 the intermediate portion of said strip of material above the hips of the wearer, and hose supporters secured to the bias edges of said strip.
